UNITED STATES PATENT OFFICE.

ALBERT E. BOULTON, OF BUFFALO, NEW YORK.

COIN-ASSEMBLING DEVICE.

1,401,957.

Specification of Letters Patent.

Patented Jan. 3, 1922.

Application filed August 4, 1919. Serial No. 315,124.

To all whom it may concern:

Be it known that I, ALBERT E. BOULTON, a citizen of the United States, residing at Buffalo, in the county of Erie and State of New York, have invented new and useful Improvements in Coin-Assembling Devices, of which the following is a specification.

This invention relates to the coin handling appliances used in banks and mercantile houses for sorting and assembling coins of various denominations preparatory to wrapping or packaging them.

Its main object is the provision of a compact and inexpensive device of this character for facilitating these operations.

A further object is the provision of an improved coin-holder which is adjustable to receive coins of various sizes, thus obviating the necessity for a variety of holders.

In the accompanying drawings: Figure 1 is a perspective view of the device. Figure 2 is a transverse section thereof through one of the coin-cells. Figure 3 is a horizontal section on line 3—3, Fig. 2. Figure 4 is a transverse section on line 4—4, Fig. 3. Figure 5 is a fragmentary perspective view of the foldable coin holder. Figure 6 is a longitudinal section of the coin hopper and adjacent parts.

Similar characters of reference indicate corresponding parts throughout the several views.

The frame or casing of the device may be of any suitable construction, but preferably comprises a back plate 10, a horizontal top plate 11, a base-plate 12, and spaced, upright front bars 13, which several parts are rigidly secured together. In the construction shown, the frame is provided with lugs or hangers 14 for securing the device to a counter, table or other support, but any other suitable fastening or clamping means may obviously be used for this purpose.

Surmounting said frame is a coin chute or hopper 15 into which the assorted coins of the same denominations are dropped. The discharge end of the chute communicates with a passage 16 in the top plate 11 through which the coins drop into the cells of a removable coin holder. It is preferred form, this holder consists of a rectangular slide, movable longitudinally and horizontally in the frame underneath the coin-chute and comprising a pair of foldable leaves or sec-

tions 17, 18, connected at their upper edges by hinges 19 and held in their closed position by hooks 20, or other suitable means. This slide or holder contains a series of upright coin cells 21 closed at their lower ends and opening at the top of the holder, so that any one of the cells may be brought under the tail of the chute by shifting the slide holder to the proper position. To predetermine these positions of the holder, it is preferably provided opposite each cell with a locking notch 22, adapted to receive a spring catch 23 carried by the base of the frame.

The coin cells are divided vertically or formed partly in each of the leaves of the slide-sections 17, 18, as shown, and to accommodate them to different sized coins, they are preferably adjustable in diameter or cross section. In the construction illustrated in the drawings, this is accomplished by constructing the front wall or half of each cell in the form of a follower 24, which is guided in an upright slot 25 in the front leaf of the coin holder, and which when in its outer position forms a cell of maximum diameter to accommodate large coins, such as quarters and nickels; and when in its inner position reduces the diameter of the cell to fit smaller coins, such as dimes and pennies. In Fig. 3, the two end-cells are enlarged to fit large-sized coins, while the three intermediate cells are contracted to fit small-sized coins.

Each follower is provided in its face with a substantially semi-circular groove or cavity, as shown, and at its sides with flanges 26 which extend into a rabbet or enlargement 27 of the slot 25. The follower is constantly urged outwardly by bow springs 28 interposed between said flanges and the bottom of the rabbet. Any suitable means may be employed for holding the followers in their inner position against the pressure of their springs. Preferably, this is effected by a vertically-sliding gravity-bolt 29, which in its lowered position engages a stop-shoulder 30 of a push-button or stud 31, projecting forwardly from the follower, and in its raised position clears said shoulder to allow the follower to spring outward under the action of its spring. The several locking bolts are guided on a face-plate 32 applied to the front slide section 17 and serving to retain the followers in their guide-slots 25. This plate has openings 33 for the passage

of said buttons. It may be screwed to the coin holder, as shown, or otherwise removably secured thereto, to permit ready access to the followers and cells in case the cells should become clogged with coins.

In order to permit of a comparatively close fit of the slidable coin-holder in the frame and yet allow the push buttons 31 and the thumb pieces 29^a of the locking bolts 29 to clear the bars 13, these bars are recessed opposite those parts, as shown at 34.

In the use of the device, a promiscuous batch of coins to be assorted and assembled for wrapping is placed upon the counter adjacent to the mouth of the chute 15, and the several cells of the coin-holder are adjusted to fit the particular denomination of coins to be assembled, for example, the followers 24 are pushed inwardly to fit dimes or pennies. The holder is next placed in the frame with the first cell registering with the chute, the automatic catch 23 snapping into engagement with the corresponding notch 22 of the holder when said cell reaches its proper position. Like coins are thus assorted and flipped into the chute whence they pile up in the cell, as shown in Fig. 2. When the first cell is filled, the holder is advanced another notch to bring the second cell under the chute, and so on, until all of the cells have been filled, when the holder is withdrawn from the frame, unfolded and placed horizontally on the counter as shown in Fig. 5. The assembled coins now lie in stacks in the half-cells of the rear leaf of the holder, in which position the stacks can be conveniently removed and wrapped or packaged in the usual manner.

If one filling of the holder is insufficient to stack all of the coins of the same denomination, the holder is replaced in the frame and the above operations are repeated without changing the adjustment of the cell followers. If, after setting up or assembling small-sized coins, it is desired to assemble larger-sized coins, as quarters or nickels, the locking bolts 29 are simply withdrawn to release the followers and enlarge the cells, as hereinbefore described.

By providing the holder with such adjustable cells, the same holder may be used for different sized coins, avoiding the necessity of furnishing numerous separate holders with cells of different diameters and materially simplifying the construction of

the device and reducing its cost, as well as rendering it more convenient in use.

I claim as my invention:

1. A coin-holder for assembling machines having a plurality of cells closed at their lower ends, each cell being open at its upper end and unobstructed throughout its length and of sufficient diameter to admit the coins and allow them to pile up in the cell from bottom to top thereof, said holder comprising hinged leaves meeting in a plane which intersects said cells longitudinally, and the open ends of the cells being adjacent to the hinged edges of the leaves. 60

2. A coin-holder for assembling machines containing a cell which is adjustable in cross section to fit different-sized coins. 70

3. A coin-holder for assembling machines containing a cell, one side of said cell consisting of a follower, and means for holding said follower in different positions. 75

4. A coin-holder for assembling machines containing a cell, one side of which consists of a follower, a spring tending to move said follower outwardly, and means for retaining the follower in its inner position. 80

5. A coin-holder for assembling machines, containing a cell, one side of which consists of a follower, said follower having a push-button, a spring tending to move the follower outwardly, and a catch arranged to interlock with said push button to hold the follower in its inner position. 85

6. A coin-holder for assembling machines having a longitudinal row of upright cells, the front wall of each cell consisting of a follower having a push-button, a face plate applied to said holder over said followers and having openings for the passage of said push-buttons, springs tending to move the followers outwardly, and locking devices carried by said face plate and arranged to engage said push buttons. 90

7. A coin holder for assembling machines comprising a slide having a cell, one wall of the cell consisting of an adjustable follower, and means for retaining said follower in different adjustments. 100

8. A coin holder for assembling machines comprising a slide having a cell, one wall of the cell consisting of an adjustable follower, a spring tending to move the follower outwardly and a locking device for retaining the follower in its inner position. 110

ALBERT E. BOULTON.
